(57) CLAIM

The ornamental design for a toy fishing rod, as shown and described.

DESCRIPTION

FIG. 1 is a top, front and left side perspective view of a toy fishing rod, showing my new design;

FIG. 2 is a bottom, rear and right side perspective view thereof;

FIG. 3 is a left side elevational view thereof;

FIG. 4 is a right side elevational view thereof;

FIG. 5 is a rear elevational view thereof;

FIG. 6 is front elevational view thereof;

FIG. 7 is a top plan view thereof;

FIG. 8 is a bottom plan view thereof;

FIG. 9 is an enlarged view of portion 9 shown in FIG. 1; and,

FIG. 10 is an enlarged view of portion 10 shown in FIG. 3.

The broken lines in the drawings depict portions of the toy fishing rod that form no part of the claimed design.

1 Claim, 10 Drawing Sheets
